HEAT-TRANSFORMING PROCESS AND APPARATUS

Application filed June 10, 1926. Serial No. 114,900.

This invention relates to processes and apparatus for transforming heat. It is especially adapted to working substances having liquid and gaseous components such as disclosed and claimed in the copending application of R. W. Davenport, Serial No. 603,998, filed November 29, 1922, and may be considered as a further development of or an improvement upon the process disclosed and claimed in the copending application of R. W. Davenport, Serial No. 15,172, filed March 12, 1925, and of the apparatus operating in accordance with such process disclosed and claimed in his copending application, Serial No. 708,936, filed April 25, 1924.

It has been found in using apparatus such as disclosed in the last named application that when a machine is started warm so much vapor is carried over to the high pressure side of the system that the condensate temporarily forms a liquid seal at the expansion device. This prevents the passage of the gaseous component and causes the system to operate on the conventional or Clausius-Rankine cycle for some time with a reduced cooling or heat absorbing effect until the accumulated condensate is blown through the expansion device and the latter begins to feed all the products of the condenser (namely, liquid, vapor and gas) into the evaporator. Thus the use of a feeding device having merely a continuously open orifice of fixed size intended to pass therethrough in a single stream all the products of the condenser does not provide sufficient flexibility of control to enable systems of the described type to operate at maximum efficiency at all times.

Among the objects of the invention are to improve the control of the circulated working substances in systems of the described type, to provide for independent regulation of the components of the working substance, to feed separate streams of liquid and of gas simultaneously into a single space, to make the feeding control entirely automatic but dependent upon or a direct resultant of the operating characteristics of the system, to devise apparatus which will accomplish the above objects, and in general to improve prior

processes and apparatus in the interest of more efficient and satisfactory service.

In one aspect the invention comprises an improved process for producing thermodynamic effects in a closed cycle system utilizing as a working substance a volatile liquid and a gas substantially inert to and insoluble in the liquid and its vapor. In its simplest form the process comprises circulating the working substance through the cycle and effecting a separate control of the liquid and gaseous components thereof at one point, whence one of the components may be fed in variable volume. The point of control or regulation is intermediate the high and the low pressure parts of the cycle. By preference the liquid component is arranged to be fed variably in proportion to the quantity of heat absorbed by the system. The gaseous component is fed continuously in fixed volume independently of the operating characteristics of the system. In another aspect the invention comprises suitable apparatus for practicing the improved process.

The float valve forms of feeding devices provided for conventional refrigerating systems are entirely unsuitable for use with working substances of the described type since such devices make no provision for feeding gas. In its apparatus aspect the invention may be considered as comprising improved means for passing both the liquid and the gaseous components of a working substance. In its preferred form it provides for feeding the gas continuously but for feeding the liquid variably or even intermittently without interfering in any way with the feeding of the gas and without affecting the volume of the gas which is fed. The variation in the feeding of the liquid component may be controlled by the level of the liquid in the feeding device.

In order to illustrate the invention and the manner of its operation one concrete embodiment of suitable apparatus for practicing the process is shown in the accompanying drawing in which the single figure illustrates in a somewhat diagrammatical manner a refrigerating system of the closed cycle or evaporator-compressor-condenser type

with the feeding device shown on a large scale and in vertical section.

In the drawing, A is a pump or compressor withdrawing the working substance mixture in gaseous and vaporized form from the top of evaporator B and discharging it at higher temperature and pressure into condenser C whence it passes through a feeding device 1 back into evaporator B. The elements comprising the closed cycle system herein shown, with the exception of the feeding or expansion device 1, may be of any suitable or desired type. The system is intended for operation with a working substance having liquid and gaseous components such as disclosed in copending application Serial No. 603,998 above referred to and operating in accordance with the process disclosed in copending application Serial No. 15,172. A typical working substance consists of evaporable liquid, such as methylene chloride, and a gas substantially inert to and insoluble in the liquid and its vapor, such as air. In accordance with the process it follows that both liquid and gas enter into expansion device 1 through inlet 2 from condenser C and that both of these components must be discharged through restricted outlet 3 to expand from the relatively higher pressure obtaining in condenser C to the relatively lower pressure maintained in evaporator B through the action of pump A.

The feeding device, to which the invention particularly relates, is arranged to pass the gaseous component continuously and to feed the liquid variably in accordance with its rate of admission from the condenser C. The feeding of the liquid is controlled by a suitable valve but the gas passes through outlet 3 in fixed volume independently of or uncontrolled by the valve. The particular form of feeding device chosen for the purpose of illustration comprises a hollow or cup shaped member 4 having outlet 3 disposed in a recess in the base of the member. The open top of member 4 is closed by a suitable cap 5 having inlet 2 therein, the cap being secured to member 4 by suitable means including cap screws 6, the mating flanges of parts 4 and 5 being arranged to form a fluid tight connection. Within the chamber 4^a is a float 7 having a hollow stem 7^a extending axially therethrough and projecting therebeyond. The lower end of the stem is formed with or has secured thereto a needle valve 7^b which cooperates with outlet 3. The valve portion of the hollow stem has a restricted opening 7^c axially therethrough which places the outlet of the feeding device in continuous communication with the upper end of chamber 4^a regardless of the position of valve 7^b. To insure accurate movement of the valve 7^b suitable means are provided for guiding float 7 comprising a bushing 8 secured in the recess in the lower

part of chamber 4^a adjacent outlet 3 and slidably receiving an enlarged portion of valve 7^b, the bushing having openings 8^a to permit passage of liquid therewithin beneath the enlarged portion of the valve. The upper end of stem 7^a is slidably received in a central opening in a guide plate 9 disposed in the upper portion of chamber 4^a. Above plate 9 and intermediate the opening end of stem 7^a and inlet 2 is a suitable deflector which may take the form of a plate 10 peripherally engaging and retaining plate 9 in place and preventing the condensed vapor or liquid refrigerant from condenser C from entering hollow stem 7^a. Plate 10 may be yieldingly maintained in place by a light coil spring 11 seated over a struck up portion of the plate and partly fitting within a recess therefor in cap 5. A screen 12 is disposed in the recess in cap 5 to bridge the inlet opening and prevent foreign matter from entering chamber 4^a. Plates 9 and 10 have openings 9^a and 10^a respectively, adjacent their peripheries to give the working substance access to the float chamber. With this arrangement the feeding device 1 causes a separation of the liquid and gaseous components of the working substance discharged from condenser C, the liquid gathering in the bottom of chamber 4^a to control the operation of float valve 7^a and to provide a liquid seal against the passage of gas past the valve, while the gaseous component of the working substance collects between plates 9 and 10 and in the upper portion of chamber 4^a and passes through hollow stem 7^a and the small communicating opening 7^c in constant volume directly into outlet 3, independently of any control by valve 7^a.

During normal operation chamber 4^a is partly filled with liquid refrigerant causing float 7 to lift and needle valve 7^b to open so that both the liquid and gaseous components of the refrigerant pass simultaneously from feeding device 1 into evaporator B. While the components of the refrigerant are separated in feeding device 1 and are conducted separately and independently toward the outlet, the arrangement is such that these fluid streams converge and meet at outlet 3 and pass in contiguity therethrough. In the form shown the liquid stream passing needle valve 7^b is generally annular in shape and the gaseous stream from the opening 7^c in the valve passes axially into the liquid stream.

From the above it will be apparent that the present invention provides improved processes and apparatus for controlling the working substances in heat transforming systems of the described type, that the control is entirely automatic and at least in part governed by the operating conditions of the system itself, that the components of the working substance are separated at one point and then directed in separate streams in contiguity through a single opening, that one

stream may be of predetermined constant volume while the other may vary in volume, that the variation of the second stream may be regulated as a direct resultant of the quantity of heat absorbed by the low pressure side of the system, and that the structural embodiment of the invention relating to the control of the working substance may be simple and inexpensive and of a type not likely to get out of order.

10 While the invention has been herein set forth both as to process and as to apparatus in what is now considered to be a preferred form, it is to be understood that the invention is not limited to the specific details thereof but covers all changes, modifications and adaptations within the scope of the appended claims.

15 We claim as our invention:

20 1. In a closed thermodynamic cycle involving the taking in and the ejecting of heat and the causing of variations in the partial pressures of a working substance having liquid and gaseous components, the process 25 of transforming heat which comprises continuously forcing the working substance through the cycle and maintaining the quantity of gas passing through the cycle substantially constant independently of the 30 quantity of heat taken into the cycle.

25 2. In a closed thermodynamic cycle involving the taking in and the ejecting of heat and the causing of variations in the partial pressures of a working substance having 35 liquid and gaseous components, the process of transforming heat which comprises continuously forcing the working substance through the cycle and separately and automatically controlling the circulated quantities 40 of the liquid component and of the gaseous component.

30 3. In a closed thermodynamic cycle involving the taking in and the ejecting of heat and the causing of variations in the partial pressures of a working substance having liquid and gaseous components, the process 45 of transforming heat which comprises continuously forcing the working substance through the cycle and varying the quantity of liquid passing through the cycle in proportion to the quantity of heat taken into the cycle and maintaining the quantity of gas passing through the cycle substantially 50 constant independently of the quantity of heat taken into the cycle.

35 4. The process of transforming heat in a closed cycle having a higher pressure part where heat is ejected and a lower pressure part where heat is taken in and causing variations in the partial pressures of a working substance having liquid and gaseous components which comprises continuously forcing the working substance through the cycle and separately and automatically controlling the quantities of the gaseous and of the 40

liquid components passing from the higher pressure part to the lower pressure part of the cycle.

5. The process of transforming heat in a closed cycle having a higher pressure part 70 where heat is ejected and a lower pressure part where heat is taken in and causing variations in the partial pressures of a working substance having liquid and gaseous components which comprises continuously forcing the working substance through the cycle and limiting the quantity of the gaseous component passing from said higher pressure part to said lower pressure part to a substantially fixed amount regardless of the operating characteristics of the cycle and of the 75 quantity of heat absorbed by said last named part.

6. The process of transforming heat in a closed cycle having a higher pressure part 80 where heat is ejected and a lower pressure part where heat is taken in and causing variations in the partial pressures of a working substance having liquid and gaseous components which comprises continuously forcing the working substance through the cycle and varying the quantity of liquid passing from said higher pressure part to said lower pressure part as a resultant of the variations 85 in the operating characteristics of the cycle 90 and maintaining a continuous movement of gas in fixed volume from said higher pressure part to said lower pressure part regardless of the operating characteristics of the cycle. 95

7. The process of producing refrigeration 100 which comprises compressing a mixture of vapor and gas to a higher total pressure, removing heat from the mixture to lower the partial vapor pressure while keeping the total pressure substantially constant, collecting the 105 condensed vapor, feeding separate streams of condensate and of gas in contiguity into a zone of reduced pressure, supplying heat to the expanding gas and to the vaporizing liquid to increase the partial pressure while 110 keeping the total pressure substantially constant, continuously repeating the above steps in a closed thermodynamic cycle, and controlling the quantity of fluid in one of said streams in proportion to the heat supplied in 115 the expanding and vaporizing step.

8. In a closed cycle system having a body of volatile liquid and a body of gas substantially inert to and insoluble in the liquid, the process of refrigeration which comprises 120 withdrawing vapor and gas from above said body of liquid, compressing the mixture of vapor and gas, removing heat from the mixture to condense the vapor, expanding separate streams of gas and of condensate in 125 contiguity into said body of liquid to absorb heat, and continuously repeating the above steps.

9. In a closed cycle system having a body of volatile liquid and a body of gas substan- 130

tially inert to and insoluble in the liquid, the process of refrigeration which comprises withdrawing vapor and gas from above said body of liquid, compressing the mixture of vapor and gas, removing heat from the mixture to condense the vapor, feeding condensate in variable volume and gas in fixed volume in contiguity into said body of liquid to absorb heat, and continuously repeating the above steps.

10. In a closed cycle system having a body of volatile liquid and a body of gas substantially inert to and insoluble in the liquid, the process of refrigeration which comprises withdrawing vapor and gas from above said body of liquid, compressing the mixture of vapor and gas, removing heat from the mixture to condense the vapor, feeding condensate in variable volume and gas in fixed volume in contiguity into said body of liquid to absorb heat and to complete the cycle, and controlling the variable quantity of condensate fed to said body in proportion to and as a delayed resultant of the quantity of heat absorbed by said body of liquid.

11. In a closed cycle system of the evaporator-compressor-condenser type utilizing a working substance having liquid and gaseous components, an evaporator, a condenser, and an expansion device between said condenser and said evaporator having means for separating the working substance discharged by said condenser into its liquid and gaseous components and for independently regulating the feeding of said components into said evaporator.

12. In a closed cycle system of the evaporator-compressor-condenser type utilizing a working substance having liquid and gaseous components, an evaporator, a condenser, and an expansion device between said condenser and said evaporator having means for separating the working substance discharged by said condenser into its liquid and gaseous components and for feeding one of said components in constant volume and the other of said components in variable volume into said evaporator.

13. In a closed cycle system of the evaporator-compressor-condenser type utilizing a working substance having liquid and gaseous components, an evaporator, a condenser, and an expansion device between said condenser and said evaporator having means for separating the working substance discharged by said condenser into its liquid and gaseous components and for feeding the gaseous component in constant volume and the liquid component in variable volume into said evaporator.

14. In a closed cycle system of the evaporator-compressor-condenser type utilizing a working substance having liquid and gaseous components, an evaporator, a condenser, and an expansion device between said condenser

and said evaporator having means for feeding separate streams of the components of said working substance from said condenser in contiguity into said evaporator.

15. In a closed cycle system of the evaporator-compressor-condenser type utilizing a working substance having liquid and gaseous components, an evaporator, a condenser, and an expansion device between said condenser and said evaporator having means for feeding separate streams of the components of said working substance from said condenser, one stream in constant volume and another in variable volume, in contiguity into said evaporator.

16. In a closed cycle system of the evaporator-compressor-condenser type utilizing a working substance having liquid and gaseous components, an evaporator, a condenser, and an expansion device between said condenser and said evaporator having means for feeding concentric streams of the components of said working substance from said condenser into said evaporator.

17. In a closed cycle system of the evaporator-compressor-condenser type utilizing a working substance having liquid and gaseous components, an evaporator, a condenser, and an expansion device between said condenser and said evaporator having means for feeding concentric streams of the components of said working substance from said condenser into said evaporator and for varying the volume of one of said streams.

18. In a closed cycle refrigerating system utilizing as a working substance an evaporable liquid and a gas substantially inert to and insoluble in the liquid and its vapor, in combination, an evaporator for containing a body of said liquid, a condenser, a pump arranged to withdraw the vapor of the liquid and said gas from said evaporator and discharge it into said condenser, and a connection between said condenser and the lower part of said evaporator having a feeding device comprising a chamber and a float valve for closing the outlet from said chamber, said valve having an opening therethrough for the passage of gas from the upper part of said chamber.

19. An expansion device for refrigerating systems utilizing as a working substance an evaporable liquid and a gas substantially inert and insoluble in the liquid comprising a member providing a chamber having an inlet at the top for the working substance and an outlet at the bottom, a float in said chamber, and a needle valve carried by said float for controlling said outlet, said valve having an axial opening arranged to connect with the upper part of said chamber for continuously conducting the gaseous component of the working substance through said outlet, and baffle means between said inlet and said

float for preventing liquid from entering said opening.

20. A feeding device of the type described comprising a hollow member providing a chamber having a restricted outlet in the bottom thereof, a cover for said member providing an inlet to said chamber, a float in said chamber, a valve carried by said float and arranged to feed liquid from the bottom of said chamber and gas from the top of said chamber to said outlet, screen and baffle means between said inlet and said float, and guide means for said float above and below the same.

21. A feeding device of the type described comprising a hollow member providing a chamber having a restricted outlet in the bottom thereof, a cover for said member providing an inlet to said chamber, a float in said chamber having a hollow stem axially thereof and projecting beyond the same at top and bottom, the lower end of said stem being arranged to form a needle valve for said outlet, a bushing in said member adjacent said outlet forming a guide for the valve end of said stem, a plate above said float having a guide opening for the upper end of said stem, and means preventing liquid from entering said hollow stem.

22. A feeding device of the type described comprising a hollow member providing a chamber having a restricted outlet in the bottom thereof, a cover for said member providing an inlet to said chamber, a float in said chamber having a hollow stem axially thereof and projecting beyond the same at top and bottom, the lower end of said stem being arranged to form a needle valve for said outlet, a bushing in said member adjacent said outlet forming a guide for the valve end of said stem, a plate above said float having a guide opening for the upper end of said stem, and a deflector plate above said guide plate, said plates having openings adjacent their periphery whereby the working fluid entering through said inlet against said deflector plate may separate into its liquid and gaseous components in said chamber, the feeding of the liquid from said chamber being controlled by said valve and the gaseous component passing therefrom independently of said valve through the hollow stem of said float.

Signed by us at Detroit, Wayne County, Michigan, this 20th day of May, 1926.

RANSOM W. DAVENPORT.

HARRY S. ESTLER.
